US00D892538S

(12) **United States Design Patent** (10) Patent No.: **US D892,538 S**
(45) Date of Patent: **** Aug. 11, 2020**

(54) **FOOD PROCESSOR**

(71) Applicant: **Capbran Holdings, LLC**, Los Angeles, CA (US)

(72) Inventor: **Robert Finance**, Los Angeles, CA (US)

(73) Assignee: **Capbran Holdings, LLC**, Los Angeles, CA (US)

(**) Term: **15 Years**

(21) Appl. No.: **29/735,945**

(22) Filed: **May 26, 2020**

Related U.S. Application Data

(62) Division of application No. 29/728,433, filed on Mar. 18, 2020, now Pat. No. Des. 889,191.

(57) **CLAIM**

The ornamental design for a food processor, as shown and described.

DESCRIPTION

FIG. 1 is a front perspective view of a food processor, in accordance with an embodiment of the present invention; FIG. 2 is a front perspective view of the food processor of FIG. 1; FIG. 3 is a bottom perspective view of the food processor of FIG. 1; FIG. 4 is a left side view of the food processor of FIG. 1; FIG. 5 is a right side view of the food processor of FIG. 1; FIG. 6 is a rear view of the food processor of FIG. 1; FIG. 7 is a front view of the food processor of FIG. 1; FIG. 8 is a top view of the food processor of FIG. 1; and, FIG. 9 is a bottom view of the food processor of FIG. 1. Any broken lines, shown throughout in the drawing figures, are included for the purpose of illustrating environmental structures and form no part of the claimed design.

1 Claim, 8 Drawing Sheets
